UNITED STATES PATENT OFFICE

2,380,338

COSMETIC CONTAINER

Orville B. Sherman, Detroit, Mich., assignor to
 Detroit Macoid Corporation, Detroit, Mich., a
 corporation of Michigan

Application August 7, 1942, Serial No. 453,971

4 Claims. (Cl. 206—56)

This invention relates to dispensing devices of the kind having their principal use in dispensing cosmetic substances or products such as lip stick, eyebrow pencil, nail polish and other cosmetic substances of a solid nature which may readily be prepared in stick form and dispensed from a small container by turning a sleeve or other member within the container so as to feed the stick longitudinally through one open end of the container into position for ready use.

An object of the invention is to provide an improved dispensing device of the foregoing class which may be produced largely or in whole of a plastic material, preferably thermoplastic in nature, thereby eliminating the use of metals, especially any metallic substance in immediate contact with the article to be dispensed.

A further object of the invention is to provide an improved dispensing device of the foregoing kind in which the various parts of the device may be readily formed and assembled together to provide a cheap, compact and efficient device for the purposes required.

Another object of the invention is to provide an improved dispensing device of the foregoing kind in which the parts may be readily and economically formed of plastic material as by injection molding and readily assembled together.

Other objects of this invention will appear in the following description and appended claims, reference being had to the accompanying drawings forming a part of this specification wherein like reference characters designate corresponding parts in the several views.

Fig. 1 is a view in elevation illustrating a dispensing device made in accordance with the invention.

Fig. 2 is a similar type of view with the cover removed.

Fig. 3 is a view in part similar to Fig. 2 but illustrating the carrier for the cosmetic material in position for use.

Fig. 4 is an enlarged vertical section taken substantially through lines 4—4 of Fig. 1 looking in the direction of the arrows.

Fig. 5 is an enlarged vertical section taken centrally through the device of Fig. 3.

Fig. 6 is a section taken substantially through lines 6—6 of Fig. 4 looking in the direction of the arrows.

Fig. 7 is a section taken substantially through lines 7—7 of Fig. 5 looking in the direction of the arrows.

Fig. 8 is an exploded view in perspective of the parts of the dispensing device.

Fig. 9 is a perspective view illustrating the manner of assembling several of the parts illustrated in Fig. 8.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The dispensing device in accordance with the present invention may, in its broader aspects, be fabricated from such material as will be found suitable for use in connection with a device adapted to dispense substances for use in the cosmetic field. In the present instance, however, it is preferred that the various parts of the device be formed of a plastic material, and more particularly a thermoplastic resinous material, and in each instance where a thermoplastic material is used the parts or elements of the device are produced by injection molding.

The structure illustrated in Figs. 1, 2 and 4 comprises an outer cylindrical sleeve or casing 10 and a tubular cover or housing 11 adapted to fit over the cylindrical casing 10 when the device is not in use, the cover 11 being open at one end and closed at its outer or top end 11a, as clearly illustrated in the drawings. The sleeve or casing 10 is open at both ends and is formed interiorly thereof with a spiral groove or shallow slot 12. An inner split sleeve 13 is adapted to be telescoped through the outer sleeve or casing 10. The inner sleeve 13 terminates at its top end in an outwardly extending annular flange 14 which is adapted to engage the adjacent end of the casing 10 when the parts are installed, as shown in the drawings. The sleeve 13 is formed with a slot 15 which extends through the bottom end of the sleeve and terminates short of the flange 14 at the upper end of the sleeve, as shown in Fig. 8. At its bottom edge the sleeve 13 is formed with two outwardly or laterally extending arcuate ribs or lugs 16. When the sleeve 13 is telescoped or passed through the casing 10 in assembling the parts, the sleeve is compressed somewhat in order to provide clearance for the ribs or lugs 16.

A follower or feed device 17 is adapted to slide longitudinally within the inner sleeve 13 when the parts of the device have been assembled for use. This follower 17 is cup-shaped and has a

hole 17a in the bottom thereof and also a transverse fin 18. The follower is also provided with a projecting lug 19 which projects through the slot 15 in the sleeve 13 into the spiral groove 12 in the cylindrical casing 10. The follower or feed device 17 is adapted to hold a lipstick 20 or other cosmetic material which is anchored within the cup 17 by means of the fin 18.

The follower 17 is first installed within the inner and outer sleeves 13 and 10 in the manner illustrated in Fig. 9, the pin 19 being lined up with the corresponding ends of the slot 15 and groove 12 whereupon the inner sleeve is turned to feed the follower 17 to the upper end of the device. After this operation a gripping ring 21 is installed 15 over the projecting end of the split sleeve 13, it being noted that this sleeve is somewhat longer than the casing 10 so as to project at its bottom beyond the lower end of the casing 10, as illustrated in the drawings. The ring 21 has a circular aperture 22 corresponding in diameter to the outer diameter of the sleeve 13. It is also formed with an annular recess 23 at the bottom face of the ring, and this recessed portion is in turn formed with two opposed arcuate notches 24 of a size to receive the ribs 16 on the sleeve 13. The ring 21 is installed over the projecting end of the split sleeve 13 by compressing the latter to provide clearance for the ribs 16, whereupon the ring 21 is slipped over the end of the sleeve and the ribs or lugs 16 are allowed to spring into interlocking engagement within the notches 24. In this manner the ring 21 and split sleeve 13 are interlocked by means of the ribs 16 and notches 24 so that the sleeve may be turned by grasping 35 and turning the ring 21 which is of a diameter to project beyond the casing 10.

In order to permanently hold the ring 21 and split sleeve 13 against disconnection and also to close the bottom end of the sleeve 13, a disk-like cap 25 is provided. This cap has a diameter and thickness corresponding to the diameter and depth of the recessed portion 23 so as to fit therein flush with the end face of the ring 21. The cap 25 also has a circular embossment or projection 26 which is of a diameter corresponding to the inner diameter of the split sleeve 13. Thus, when the disk 25 is pressed into the recessed portion 23 in the ring 21 the embossment 26 fits snugly within the split sleeve 13, thereby holding the split end of the sleeve rigidly against contraction. After installation of the closure disk 25 with the ring 21 these parts may be heated sufficiently to fuse or seal them together permanently. Thus, when the device is completed the parts 21 and 25 are united together as a single member which is locked to the split sleeve 13 and is also rotatable to turn this sleeve and thereby reciprocate the follower 17 within the telescoped sleeves 13 and 10. In the present instance the annular lip or flange 14 projects slightly beyond the casing or sleeve 10 to provide a bearing for the cover 11. The lower end of the sleeve or casing 10 is accordingly provided with tapering ribs 10a projecting outwardly the same distance as the flange or lip 14 and providing a means by which the cover 11 when forced over the casing 10 is wedgingly held in position.

I claim:

1. A dispensing device of the class described, 70 comprising a cylindrical casing having a spiral groove at the inner wall thereof, an open ended sleeve extending through said casing and split longitudinally by means of a slot extending through the bottom end of the sleeve but termi-

nating short of the opposite end thereof, a follower within said sleeve having a lug extending through said slot into said groove so as to be fed longitudinally within the sleeve upon relative rotation of the sleeve and casing, said sleeve having an open split end portion extending beyond the end of the casing, a gripping member having an interlocking connection with said end portion and including a part fitting the outer diameter of the sleeve and a part fitting the inner diameter thereof, said interlocking connection comprising an outwardly projecting rib on the split end of the sleeve fitting into a notch in said first named part.

2. A dispensing device of the class described, comprising a cylindrical casing having a spiral groove at the inner wall thereof, an open ended sleeve extending through and fitting the inner diameter of said casing and split longitudinally by means of a slot extending through the bottom end of the sleeve but terminating short of the opposite end thereof, a follower within said sleeve having a projection extending through said slot into said groove so as to be fed longitudinally within the sleeve upon relative rotation of the sleeve and casing, said sleeve having an open split end portion extending beyond the end of the casing and provided with an outwardly projecting lug, a gripping member on said split end portion including a ring part having a central aperture corresponding in diameter to the outer diameter of said end portion and also having a notch to receive said lug upon compressing said split end to pass it through said aperture, said member also including a disk part having a portion extending within and fitting the inner diameter of said split end portion, said parts being permanently secured together.

3. A dispensing device of the class described, comprising a cylindrical casing having a spiral groove at the inner wall thereof, an open ended sleeve extending through said casing and split longitudinally by means of a slot extending through the bottom end of the sleeve but terminating short of the opposite end thereof, a follower within said sleeve having a lug extending through said slot into said groove so as to be fed longitudinally within the sleeve upon relative rotation of the sleeve and casing, said sleeve having a split end portion extending beyond the end of the casing and provided with an outwardly projecting arcuate rib or ribs, a gripping ring having a central aperture corresponding in diameter to the outer diameter of said split end portion and through which said split end may be passed upon compressing the same to provide clearance for said rib or ribs, there being an annular recessed portion around said aperture at the bottom face of the ring, said recessed portion being notched to receive said rib or ribs when the split end of the sleeve is passed through the said aperture, and a disk-like cap fitting into said recessed portion and having a circular boss corresponding in diameter to the inner diameter of the said split end portion of the sleeve and fitting therein.

4. A dispensing device of the class described, comprising a cylindrical casing having a spiral groove at the inner wall thereof, an open ended sleeve extending through said casing and split longitudinally by means of a slot extending through the bottom end of the sleeve but terminating short of the opposite end thereof, a follower within said sleeve having a lug extending through said slot into said groove so as to be fed longitudinally within the sleeve upon relative ro-

tation of the sleeve and casing, said sleeve having a split end portion extending beyond the end of the casing and provided with an outwardly projecting arcuate rib or ribs, a gripping ring having a central aperture corresponding in diameter to the outer diameter of said split end portion and through which said split end may be passed upon compressing the same to provide clearance for said rib or ribs, there being an annular recessed portion around said aperture at the bottom face 10

of the ring, said recessed portion being notched to receive said rib or ribs when the split end of the sleeve is passed through the said aperture, and a disk-like cap fitting into said recessed portion and having a circular boss corresponding in diameter to the inner diameter of the said split end portion of the sleeve and fitting therein, said cap and ring being permanently secured together. 5

ORVILLE B. SHERMAN.
